TELEPHONE SYSTEM

Hans Tatzl, Vienna, Austria, assignor to Siemens & Halske Aktiengesellschaft, Wernerwerk, Siemensstadt, near Berlin, Germany

Application August 25, 1934, Serial No. 741,378
In Germany September 5, 1933

8 Claims. (Cl. 179—27)

In telephone systems with relay selectors in which incoming lines cross a plurality of outgoing lines of similar direction of traffic, the requirement is often set that, during a connection between an incoming and an outgoing line another incoming line is to be connected up to the portion of the outgoing line remaining in the exchange. This case occurs, for instance, more particularly in private branch exchange systems 5 when it is a question of changing over a public exchange connection to a definite subscriber's station. The public exchange line is in this case the outgoing line, and the subscriber's line the incoming, and in the following description the 10 public exchange line is also considered as an outgoing line when it is a question of a changeover of an incoming public exchange connection from the main station receiving the public exchange call to the wanted private branch station. Further, the connection of a subscriber's line to an 15 outgoing line is also then necessary when it is a question of setting up an enquiry connection.

The object of the invention, now, is to effect 20 these necessary couplings, existing connections being maintained, to a definite outgoing line, reducing as much as possible the number of the 25 numerical impulse receivers necessary for reaching the wanted line and the auxiliary devices initiating and effect the coupling, and this is 30 achieved in that, through the switching operation (key pressure) which initiates the connecting up of a speaking station to an existing connection (setting up of incoming public exchange 35 connections, enquiry connections), switching means are influenced which bring a numerical impulse receiver over the outgoing line under the influence of the speaking station carrying out the switching operation, and prepare the coupling of the station accessible over the numerical impulse receiver to the seized outgoing line.

An embodiment of the invention is shown in the drawings 1 to 6. The invention is not limited to the embodiment. Only the switching details necessary for understanding the invention have 40 been shown.

It is a question of a full automatic relay exchange having two public exchange lines and a house line. The public exchange lines have the symbol ALI and ALII, while the house line is 45 designated by HL. The setting up of the connections takes place in employing relays. No rotary selectors, therefore, are used. The subscribers privileged in respect to public exchange calls possess stations having earthing keys, while 50 the non-public exchange privileged stations have

no earthing key. A main station with special service facilities exists for the connecting up of incoming public exchange traffic.

House traffic takes place as follows: After removing the handset the subscriber selects the 5 number of the wanted speaking station, which is then automatically called. During the call the caller receives the free signal. As soon as the called party replies, the ringing current is interrupted, and the speaking connection established. 10 If after the conclusion of the conversation both subscribers hang up the handset, the connection is released, and the connection assembly is 15 free for further seizure. If the wanted subscriber is busy, or if the house junction line is not free, the calling party receives the busy signal.

If the main station has the intention of carrying on an internal conversation, then, in contradistinction to a normal speaking station, the main station must first press the house key. A 20 house lamp at its service apparatus then lights; selection of the wanted subscriber's station then takes place.

If a subscriber entitled to public exchange calls 25 wanted a connection to a subscriber of the public exchange, he presses, after lifting off his handset, the earthing key at the station. He is thereby automatically connected to a free junction line to the public exchange, and the house assembly seized on lifting off the handset is, after 30 switching through has taken place, again free. A public exchange line can be reached even when the house assembly is busy. After switching through to the public exchange, selection takes 35 place in usual manner after waiting for the public exchange signal. If both public exchange lines are busy, the subscriber receives the busy signal during the duration of key pressure. During a public exchange conversation a supervisory lamp lights for the time being at the main station, 40 which lamp is associated with the busy public exchange line. The stations non-privileged in respect to public exchange calls, since they have no earthing key, cannot reach the public exchange. 45

If the main station wishes to conduct a public exchange conversation, the station presses the key of a free public exchange junction line. It is thereby directly connected through to the public exchange. After waiting for the public exchange signal, dialling of the public exchange subscriber can be begun. During the conversation the supervisory lamp of the used public exchange line lights up. If both public exchange lines are busy, the operator recognizes this by 55

the lighting up of both supervisory lamps at her service station. If, nevertheless, she presses one of the public exchange keys, all speaking stations receive the ticking signal.

- 5 In calling up the exchange by a subscriber of the public exchange, the alarm bell of the service station rings, and at the same time the calling lamp of the public exchange line lights upon which the call is arriving. The operator of the 10 main station presses the public exchange key in question, and is thereby enabled to take over directly the public exchange conversation.

If an internal speaking station of the exchange is desired by the public exchange subscriber, the 15 operator, after taking the instructions, presses the connecting key and dials the wanted internal subscriber. The latter takes over the public exchange conversation by pressing the key, while the main station hangs up. If the wanted 20 internal subscriber is carrying on at the moment in question an internal conversation, the operator, by pressing the listening-in key, can enter the circuit of the public exchange conversation and notify the wanted internal speaking station of 25 the existing call.

The connection of the operator to the existing conversation is effected by free signals to the two speaking subscribers. There is similarly a free signal when the operator connects herself to 30 an existing public exchange conversation.

If a public exchange conversation exists, and if enquiry is to be held, the enquiry subscriber presses the earthing key of his station and dials the wanted subscriber. The public exchange loop 35 is held during the internal conversation, but the public exchange subscriber cannot concurrently hear the enquiry conversation. After termination of the enquiry, either the subscriber called in enquiry can take over the conversation by key pressure (change-over), or the enquiring subscriber, by again pressing the key, switches himself back, on his part, to the public exchange line, and can thereupon continue the public exchange conversation. If, during a public exchange 40 conversation, enquiry to the main station is necessary, the key is to be pressed, as previously, and the number of the main station to be dialled. At the service station the calling lamp of that 45 public exchange line then flickers on which the enquiry takes place. The operator thereupon presses the key associated with this public exchange line, and can conduct the enquiry conversation. If she wishes to take over the public exchange conversation, she presses the connecting 50 key located at her service station.

Two of the internal speaking stations are provided with night switching. If a public exchange call arrives at the main station and if it is not answered by the latter within a certain time, the 55 call is automatically passed on to the night station. Passing on of the call can be effected in two ways:

(1) The call arriving on the public exchange line ALI is passed on to one night station, the 60 call arriving on the second public exchange line being passed on to the second night station.

(2) The public exchange calls of both public exchange lines arrive on the same night station, and are only answered by the latter.

70 Changing over for these two kinds of traffic takes place, as may be desired, at the distributor.

At night the public exchange calls pass directly to both night stations, by-passing the main station, since now the night switch of both public 75 exchange lines is changed over. In the case of

passing on the call, as also in the case of night switching, the call is answered merely by taking off the receiver and listening, i. e., without pressing the key.

In the following the individual circuits will be 5 described:

The six figures of the drawings are to be so placed together that Figs. 1 and 2, Figs. 3 and 4, and Figs. 5 and 6 lie side by side.

Fig. 1 shows the subscribers' connections (the 10 main station is arranged at the top on the left), the two public exchange lines ALI and ALII and the house line HL.

Fig. 2 shows the sets of coupling relays.

Figs. 3 and 5 show the devices for the two public 15 exchange lines.

Fig. 4 shows the house selector HW, while Fig. 6 shows the enquiry selector RW and also the arrangements for giving signals.

A. HOUSE TRAFFIC

20

(a) Traffic of normal stations

If a subscriber of the private branch exchange system, for instance, subscriber N2, wishes to set up a house connection, to line N3, for example, 25 the following circuit is closed for relay R2 by removing the receiver: earth, battery, resistance 60Wi, (Fig. 1) contacts 1c2, 2b2, 3a2, winding I of relay X2, subscriber's station N2, winding II of relay X2, contacts 4a2, 5b2, 6c2, 7w2, 8IIr2, 30 line 600 (Fig. 1 and Fig. 2), 9IIh, winding of the relay R2, line 24 (Figs. 2 and 4) contacts 109v3, 110bes, 111v1, 112n, earth. Relay R2 energizes in this circuit. Through closing of contact 11r2 35 the following circuit is closed for the impulse relay J, Fig. 1: earth, battery, winding II of relay J, contact 11r2, winding I of relay J, earth. The following circuit for guard relay CH and transfer relay C2 is closed over contact 12j: earth, battery, winding of the relay CH, contact 12j (Fig. 40 4), line 22 (Fig. 4 and Fig. 2), winding of relay C2, contacts 13r2, 14r1, 15ch, earth. Relays C2 and CH energize. The calling line is connected up over contacts 16c2 and 17c2 to the house junction line HL. Since, through actuation of these 45 two c2-contacts the circuit of relay R2 is opened, relay R2 falls away. The feeding relay J is now held over the subscriber's loop and relays C2 and CH hold over the contact 18c2, line 23 (Figs. 2 and 4) and the resistance 19Wi to earth. 50 Through contact 15ch earth is removed from the chain of r-contacts (contacts 14r1, 13r2, etc.) in order to prevent the energization of further C-relays in the case of the existing house connection. The following circuit for release relay VI 55 (Fig. 4) is closed over contact 20i: earth, battery, resistance 21Wi, winding of relay VI, earth, so that the impulse contact 12i is bridged by the contact 25v1, and the connect relay C2 and guard relay CH can continue to hold during the impulse transmission, over contacts 18c2. Over contact 27v1 (Fig. 4) the energizing circuit for the series relay V2 as also the holding circuit for release relay VI is prepared. Further, through contact 60 27v1 the following circuit for the relay An of the house selector HW (Fig. 4) is closed: earth, battery, winding of relay An, contacts 28ab1, 27v1, earth. The house selector is connected to earth over contact 29an, while over contact 30an the 70 signalling circuit for the free signal or the busy signal is prepared.

Upon the return of the dial switch, the feeding relay J is left as often currentless as the subscriber's loop is broken by the dial switch. Upon 75

the first falling away of relay J the relay V2 (Fig. 4) energizes, in the following circuit: earth, battery, resistance 21Wi, contact 29j, winding of relay V2, contact 21v1, earth. The relays VI and 5 V2 then hold in known manner during the impulse transmission, owing to delayed action in falling away, through short circuiting. The relay V3 is energized over contact 30v2, in the following circuit: earth, battery, winding of relay V3, contacts 30v2, 28ab1, 27v1, earth. A circuit for the winding I of relay IH of the house selector HW is closed over contact 31v3: earth, battery, winding I of relay IH, contacts 31v3, 32n, 29an, 27v1, earth. 10 Over contact 33j the following circuit for relay K is closed on the first deenergization of J: earth, battery, winding of relay K, contacts 34l, 35p, 33i, 29an, 27v1, earth. Relay K energizes. Over contacts 36k and 43k the following circuit for 15 winding II of relay IH is closed, relay IH having been operated: earth, battery, resistance 37Wi, contacts 38p, 36k, winding I of relay IH, contacts 39IIIh, 40Vh, 41VIIh, 42IXh, 43k, 29an, 27v1, earth. The relay IH further holds over its own 20 contact 44IH and its winding II.

When, after termination of the first impulse, the relay J again energizes, the relay L is energized over contact 45j, which relay was hitherto short circuited by contacts 46k and 33i. The relay K continues to hold in the circuit of relay L through contact 33j. The relay L energizes the relay N over its contact 47l, and the former continues to hold over its contact 32n as long as the selector remains seized. Over contact 48n, Fig. 25, the signalling chain (relays O1-O4) and the ringing relay are started.

If, upon a second impulse, the relay J is again currentless, relay K falls away, since, through changing over contact 33i, its circuit is interrupted. Relay IH is also currentless through changing over contact 43k of relay K, and only the relays L and IH continue to hold, relay L remaining energized over its winding I and contacts 34l, 35p, 33i and relay IH over its contact 40 50IIIh and its winding II and contacts 51IVh, 52Vh, 53VIIIh, 54Xh, 43k, 29an, 27v1, earth. Further, over the fallen-away contacts 36k and 43k and the now-actuated contact 55v3, the relay 45 IH is energized over its winding II.

50 Upon termination of the second impulses the relay J is again energized. Relay L is released at contact 35j, but relays IH and IIIH continue to hold.

The foregoing switching operations are repeated in the transmission of further impulses, in such manner that the relays K and L are energized after odd impulses, and after even impulses the relays K and L have fallen away.

When the impulse transmission is now terminated at the end of the third impulse, the counting relay of the relay selector which corresponds to the number of impulses dialed (the relay IIIH) is held energized for the time being over its II winding. In the relay selector there are also provided the relays IVH to XH, in addition to the relays IH to IIIH. When, after impulse transmission has taken place, the relay J again remains continuously energized, series relay V2 falls away with delayed action, and energizes the 55 changeover relay P over its contact 60v2. Relay V3 is also currentless through opening of contact 38p. The contact 38p opens the circuit for that counting relay which corresponds to an impulse transmission higher by one than was dialled 60 (for instance, in dialling the number 3 the relay

IVH has momentarily energized over a contact of relay IIIH, but is now deprived of current through contact 38p).

The testing and first ringing are limited by the interval between the energization of relay P 5 and the falling away of slow-acting relay V3.

If the called subscriber's line N3 is free, the relay P1 energizes over the ringing circuit (Fig. 1): earth, battery, resistance 60Wi, contacts 61c3, 62b3, 63a3, winding I of relay X3, subscriber's 10 station N3, choke Dr2, winding II of relay X3, contacts 64a3, 65b3, 66c3, 67w3, 68IIIr, of relay IIIH of the enquiry selector RW, (Fig. 6) line 70 (Fig. 1 and Fig. 2), contacts 69IIIh (Fig. 2) of relay IIIH of the house selector, contacts 71v3, 15 72p, winding I of relay P1, earth to the source of alternating current, Fig. 6. The circuit for relay Fr is closed over contact 73p1 (Fig. 4). This relay holds over its contacts 74fr and at 20 75fr the free signal is now inductively communicated to the calling subscriber over the relay J. The free signal is a rattling in rhythm with the ringing impulse. Upon energization of relay P1 the first ringing signal is directly communicated to the wanted subscriber. 25

Further ringing takes place in known manner after timer relay V3 restores: From the interrupted generator lead through winding I of ring-cut-off relay Ab1.

As soon as the called subscriber removes the 30 handset, the ring-cut-off relay Ab1 energizes through the continuous current flowing over the subscriber loop, in the following circuit (Fig. 1): earth, battery, resistance 60Wi, contacts 61c3, 62b3, 63a3, winding I of relay X3, subscriber's 35 loop, winding II of relay X3, contacts 64a3, 65b3, 66c3, 67w3, 68IIIr, line 70 (Fig. 1 and Fig. 2), 69IIIh, contacts 80v3, 81fr, winding I of relay Ab1, contact 82rf (relay not shown), earth. Relay Ab1 holds over its winding II and contact 40 83b1. The operating contact 83ab1 (Fig. 4) closes a circuit for the transfer relay C3 associated with the subscriber N3. Relay C3 energizes over the changed-over selector contact 85IIIh, and continues to hold over its contact 86c3. At contacts 45 90 and 91, C3, Fig. 1, relay C3 switches the line 3 over to the house line HL. Through changing over of the contact 28ab1, the relay An of the house selector HW is without current. Through falling away of relay An the circuits of relays 50 Fr, K, L, P, and IIIhN are interrupted.

With switching through of the called subscriber the speaking condition is reached. Both subscribers receive feeding current over the relay J. During the conversation the following relays are 55 energized: J, VI, Ab1, CH and the relays C2 and C3 of the two speaking subscribers.

The connection is released as soon as the two subscribers have replaced their handsets. The relay J is without current through opening of 60 the two subscribers' loops, and short circuits the relay VI which falls away with delayed action and breaks the circuit of relays Ab1, C2 and C3 and CH, whereby these relays fall away. The normal state of rest is then re-established. 65

If the called subscriber is busy, the relay P1 in contradistinction to the above (the called subscriber is free) does not energize, since the loop for the relay P1 is interrupted through the changed-over contacts of one of the transfer relays A3, B3, and C3. The relay Fr, therefore, also does not receive any current and the subscriber receives a busy signal inductively over contacts 75fr to the relay J. The calling subscriber thereupon replaces his receiver. 75

If the house line is busy, and a further subscriber takes off his handset to make a call, the latter similarly receives a busy signal. In the circuit of line relays R (R2, R3, etc.) direct earth is lacking. This is rather formed only over the buzzer relay Su, which possesses such a high resistance that the line relays R cannot energize. The relay Su, however, energizes and interrupts the circuit through its own contact 10su. It falls away, therefore, and immediately reenergizes. The busy signal is generated through this periodical opening and closing of the circuit.

(b) *Traffic of the main station HSt with a normal station*

If the main station HSt wishes to set up a house connection, it removes the handset, whereby the relay HU (Fig. 2) is energized in the following circuit over the changed-over switchhook (shown in Fig. 2): earth, battery, winding of the slow-acting relay HU, hook switch HUm, earth. Then the house key HT at the station is pressed. The relay H is thereby energized in the following circuit: earth, battery, winding of relay H, key HT, key T2, key T1, switchhook HUm, earth. The relay HH is energized over contact 109h. The relay H holds over contact 101hh, the relay H also, after releasing the key HT. Both relays then hold throughout the conversation. The house lamp HL is connected up over contact 102h during the entire duration of conversation. The service station is connected to conductors a and b (associated with the house junction line HL) over the contacts 104hh and 105hh (Fig. 1), so that the relay R1 can now energize in the following circuit over the closed subscriber's loop: earth, battery, resistance 60Wi, contact 107cl, a lead of the junction line of the main station HSt, contact 104hh, subscriber's station, contacts 105hh, 106cl, 108lh, winding of relay R1, line 24 (Fig. 2 and Fig. 4), contacts 109v3, 110bes, 111v1, 112n, earth. After operation of relay R1 the same switching operations takes place as previously described in the case of traffic at a house station. The relay J is connected up over contact 115rl, while the relay C1 is caused to energize over contact 116rl. This relay holds over its contact 117cl. In the circuit of relay C1 the relay Ch again becomes effective. The relays V1 and V2 are brought into operation over the impulsive contact. Impulse transmission then takes place in similar manner and influences the house selector HW, as already previously described.

B. OUTGOING PUBLIC EXCHANGE TRAFFIC

Assuming the subscriber N2 wishes to set up a public exchange connection, he presses his earthing key Te2 after or while removing the receiver. The relay X2, constructed as a differential relay, thereby energizes, in the following circuit: earth, battery, resistance 60Wi, contacts 1c2, 2b2, 3a2, winding I of relay X2, key Te2, earth. Connecting up of the private branch station to a free public exchange line is initiated over the contacts of relay X2. For public exchange calls, relays A1-A4, Fig. 2, are associated with the public exchange line ALI, and relays B1-B4 are associated with the public exchange line ALII.

For the following explanations it will be assumed that the public exchange line ALI is already seized, but the public exchange line ALII is free. Therefore, the guard relay Sp1 (Fig. 5) of this public exchange line is then energized, so that the relays A (Fig. 2) of the private branch station in question cannot be energized over the

x-contacts. With the public exchange line ALI busy, the following circuit for the relay A2 is broken (Fig. 4) through the contact 125sp1: earth, battery, resistance 120Wi, contacts 127m, 125sp1, 128h1, (relay H1, see Fig. 5), 129eb, line 130 (Fig. 4, Fig. 2), contacts 131t2, 132a2, winding of relay A2, contact 133x2, line 134 (Fig. 2, Fig. 4), contacts 135xa, 136e, 137ga, earth. The relay A2 cannot therefore energize. Through closing of contact 135x2 the following circuit is closed for the relay B2 (Fig. 4): earth, battery, resistance 126Wi, contacts 127m, 136sp1, 137sp2, 138h2, 139ea, line 140 (Fig. 4), line 140 (Fig. 2), contacts 141t2, 142b2, winding I of relay B2, contact 135x2, line 143 (Fig. 2), line 143 (Fig. 4), contacts 144xb, 145e2, 146gb, earth. The relay B2 energizes in this circuit to connect the calling private branch station N2 to the public exchange line ALII over contacts 150b2, and 151b2. At contacts 142b2 and 170b2, Fig. 2, relay B2 switches itself into a holding circuit which includes winding II of relay T2 and relay GB. Relay T2, at contacts 131t2 and 141t2 opens points in the circuits through which relays A2 and B2 can energize to cause seizure of a main-exchange trunk line from the calling line N2, while relay GB, at its contact 146gb, removes a shunt from around relay EB, permitting this relay to operate in series with relays B2, T2, and GB.

When line N2 is switched over from the house equipment at contacts 2 and 5 of relay B2, to the main-exchange line ALII, through contacts 150b2 and 151b2, the local, house equipment is thereby freed and the line ALII seized. The feeding relay S2 of this line is energized in the following circuit: earth, battery, winding II of relay S2, contacts 150b2, 3a2, winding I of relay X2, subscriber's loop, winding II of relay X2, contacts 4a2, 151b2, winding I of relay S2, earth. Relay S2 bridges retard coil Dr21 across the outgoing conductors at contact 174s2. The associated release relay Q21, Fig. 5, energizes in the following circuit: earth, battery, resistance 153Wi, winding of relay Q21, contact 152s2, earth. The circuit of the calling relay Ar2, Fig. 3, of the public exchange line ALII is broken through contact 160q21. The circuit for the relay Sp2 of the public exchange line AL2 is closed over contact 161o21 and resistance 162Wi. At the same time the supervisory lamp U12 of the public exchange line ALII, in a circuit in parallel with the relay Sp2, lights up, since contact 163u2 is closed. Relay Sp2 guards by its contact 137sp2 (Fig. 4) the seized public exchange line against any further seizure, since the energizing circuit for the coupling relays B (B1-B4) of the remaining subscribers is broken. The relay B2 (Fig. 2) holds over its contacts 170b2, and thereby causes also the relay T2 and the relay GB to energize. The relay T2, through its contact 131t2, breaks a further point in the circuit of relay A2 of the first public exchange line, in order not to bring about also a seizure of the possibly free first public exchange line in the case of subsequent enquiry. Through changing over of contact 146gb the short circuit for the relay EB is removed, so that this becomes energized. The relay Y2 (Fig. 5) is energized over its winding I over contact 167z2, 165eb, and 171q21. Relay Y2 at contact 270y2, locks itself in series with the I winding of relay Z2, but relay Z2, being short-circuited at 165eb, does not respond at this time. The talking circuit over ALII is prepared at contacts 168y2 and 170y2. The common relay E (Fig. 4) 75

is caused to energize over contacts 161eb and 162q21.

If the key Te2 is now released, the differential relay X2 restores. The circuit for the relays EB, B2, T2, and GB is interrupted through opening of contact 135x2 (Fig. 2). Relay EB, restores immediately, but slow-acting relays B2 and GB do not. At contact 161eb, relay EB completes a new holding circuit through contacts 162q21 and 165x2 for relays B2, T2, and GB, at the same time permitting relay E to restore again. Through opening of contact 166eb, the short circuit for the winding I of relay Z2, Fig. 5, is removed, so that the relay Z2 is caused to energize in series with relay Y2, winding I. The relay Z2, through opening of contact 167z2 and closing of contact 168z2, connects up its winding II and the winding II of relay Y2. The relays Y2 and Z2 hold during the duration of the public exchange connection.

The subscriber, after switching through to the public exchange, waits for the dial signal from the public exchange, and then begins with the selection of the wanted public exchange subscriber. Upon the first impulse, the relay S2 changes over its contacts. The short circuit for the series relay Q22 (Fig. 5) is removed through contact 152s2, so that also this relay energizes (contact 171q21 is closed). Relays Q21 and Q22 hold during the impulse transmission. The public exchange line is broken backwards by the contacts 172q22 and 173q22, Fig. 3. At the same time, over contact 172q22 the choke DR21 which was connected up after changing over of contact 174s2 is short circuited for the purpose of satisfactory impulse transmission.

The public exchange loop is interrupted in rhythm with the interruptions of the loop produced by the dial switch, through contact 174s2, so that the impulses to the public exchange are given. After dialling, the subscriber is called, and the calling subscriber receives from the public exchange, the public exchange subscriber being free, the free signal. If it happens, after dialling, that the wanted subscriber is busy (busy signal from the public exchange), the connection is released by hanging up.

When the called subscriber replies, conversation can be carried on. Feeding of the internal subscriber takes place over the relay S2. The following relays are energized during the public exchange conversation: S2, Fig. 3, Q21, Sp2, Y2, and Z2, Fig. 5, B2 and T2, Fig. 2, and GB, Fig. 4.

The connection is released through hanging up the handset by the private branch station. The feeding relay S2 thereby falls away, and through its intermediary the whole of the remaining relays.

If a private branch station desires to set up a public exchange connection and, if at this moment both public exchange lines are already busy, the private branch station receives the busy signal as continuous hums during key pressure. Since the Sp-relays (Sp1 and Sp2) of both public exchange lines, as previously described, are energized, none of the A and B relays (A1 to A4, B1 to B4) can operate, contacts 125sp1 and 131sp2 being open.

(b) *Outgoing public exchange traffic of the main station with operator's facilities*

After the removing of the handset at the main station the relay HU, Fig. 2, is energized through hookswitch HUM, Fig. 2, as already described, and prepares the energizing circuit for the coupling relays A1, B1, respectively, which relate the

main station to the public exchange lines through its contacts 180hu, 181hu, respectively.

The operator, in order to obtain a public exchange connection, presses the public exchange key associated with a free public exchange line, for instance, T1 for public exchange line ALI, the relay A1 thereby energizing through its II winding. At the same time the relay Y1 (Fig. 5) is energized over its winding I, since the line 185 of Fig. 5 leads to the key T1 in Fig. 2. The relay A1, by means of its contacts 186a1 and 187a1, connects the service station to the public exchange line ALI. The feeding relay S1 is energized over its windings I and II in known manner over the subscriber's loop. The release relay Q11, Fig. 5, of the public exchange line ALI is energized at contact 188s1. The resistance 189Wi is connected in the circuit of relay Q11. The relay Q11 holds over its contact 190q11. At contacts 180hu and 262a1, Fig. 2, a holding circuit for relay A1 (winding I) is closed through contacts 650xa, ea, and q11.

The relays HU and A1 hold during the duration of the connection. The relay Y1 connects through the public exchange line by its contacts 191y1 and 192y1. The relay S1 connects the loop relay Dr11 in the public exchange line by its contact 193s1. The calling lamp AL1 is connected up over contact 194a1 (Fig. 5). After relay Q11 is energized, the supervisory lamp UL1 lights, since contacts 195q11 and 196u1 are closed. Both lamps light during the entire duration of the public exchange conversation. The relay Sp1, in the circuit of which is connected the resistance 197Wi, is similar energized over contact 195q11. Through changing over its contact 125sp1 (Fig. 4), the relay Sp1 guards the public exchange line ALI against a further seizure through one of the remaining private branch stations.

When the key T1 is again released, the until then short circuited relay Z1 energizes over its winding I, opens its contact 199z1, and closes its contact 200z1, and therefore a circuit for its winding II and the winding II of relay Y1. Both relays hold over contact 201y1.

Numerical selection and ringing of the public exchange subscriber takes place as already described. After removing the handset by the subscriber of the public exchange, conversation can be carried on. When, at the conclusion of the conversation, the main station hangs up the handset, relays S1 and HU are first of all without current and, through their intermediary, all remaining relays. The lamps AL1 and UL1 are also extinguished.

C. *INCOMING PUBLIC EXCHANGE TRAFFIC*

If the exchange is called by the public exchange, the calling relay of the public exchange line (Ar1), of the public exchange line ALI or Ar2 of the public exchange line ALII, concerned is energized dependent upon the ringing current. The relay H1 of the public exchange line ALI is energized over contact 220ar1, or the relay H2 of the public exchange line ALII is energized over contact 221ar2. The relay H1 holds over its contact 222h1 and its winding II in the following circuit in which relay H31 also energizes: earth, battery, winding of relay H31, winding II of relay H1, contacts 222h1, 223q11, earth. Relay H2 correspondingly holds over its contact 224h2 and contact 225q2, and causes relay H32 to energize. The thermo-relay Th1 of the public exchange line ALI heats over contact 222h1, and the ther-

mo-relay T_2 of the public exchange line ALII over the contact 224h2. The contacts 226w11 and 227w12 are still closed. The further connection of the ringing is prepared through the thermo-relay. At the service station (Fig. 2) the alarm bell sounds, which bell is connected to potential over contact 228h31 and 229h32, respectively. Moreover, the calling lamps AL1 and AL2 respectively are connected up over contacts 230h31, 231h32, respectively. The calling lamp of the public exchange line on which the call arrives is therefore caused to illuminate.

Upon the call from the public exchange, the main station removes the handset and presses the T-key of the public exchange line on which the call has taken place, i.e., the key T1 or T2. The circuits are then set up as already described in the case of outgoing public exchange traffic. The relays Q1, Q2, respectively, are energized over the S-relays (S1, S2, respectively) which have energized after closure of the loop, so that now the call-holding relays H1 and H31, or H2 and H32 respectively are without current. The calling lamps AL1, AL2 respectively further light up over the contacts 104a1, 249b1 respectively. The red supervisory lamp also burns during the duration of the conversation, viz., dependent on the contacts 105q11, 101q21 respectively.

After energization of the Y-relay of the public exchange line in question (relays Y1, Y2 respectively), the public exchange line is connected through to the main station, and conversation can be carried on. Release of the connection takes place as already previously described.

If the operator upon a call from the public exchange is carrying on an internal conversation, or a public exchange conversation on the second public exchange line, she is made aware of the call by the lighting up of the calling lamp of the first public exchange line. If she is carrying on a house conversation, she has the possibility of terminating this by hanging up the receiver and of taking over the public exchange conversation by pressing the public exchange key associated with the public exchange line in question. If, however, she is carrying on, for instance, a public exchange conversation on the first public exchange line upon the arrival of a call on the second public exchange line, she can either terminate the first public exchange conversation by hanging up the handset, and take over the second by pressing the other public exchange key, or she may press the second public exchange key without previous hanging up. The first public exchange conversation is thereby held (waiting condition) and the second public exchange conversation can be carried on. The waiting condition for the first subscriber is reached in the following manner.

Upon arrival of the second public exchange conversation on the second public exchange line, the operator presses the public exchange key T2. The relay B1 is thereby energized. Since the relay A1 is energized through the already existing public exchange conversation, a circuit is temporarily closed for the windings I of relays U1 and U2 over the contacts 250a1 and 251b1. The holding circuit of relay A1 of the first public exchange line which was closed over contact 262a1 is interrupted through contact 261u1, so that this relay falls away. The connection on the public exchange line AL1 is held, after falling away of relay A1, over the new current path for the relay S1 of the first public exchange line: earth, battery, resistance 252Wi, contacts 253u1, 186a1, line

620 (Fig. 1 and Fig. 3), winding I of relay S1, earth. Since, therefore, the relay S1 is further held, the connection of the first public exchange line does not release. After falling away of relay A1 the relay U1 (Fig. 2) holds further over its winding II and its contact 253u1 while the relay U2 again falls away. As the relay B1 remains energized through the depressed public exchange key T2, the falling away contact 263u2 now closes the holding circuit for the relay B1, so that this relay also remains energized after release of the key T2. (Contact 264b1 is closed.)

Also responsive to the operation of key T2, relay Y2, Fig. 5, operates over conductor 27 as herein-before described, with the result that relay Z2 operates also through contact 171q21 of the energized release relay Q21, when the key T2 is released. The main station is now connected over contacts 254b1 and 255b1 to the second public exchange line ALII. The flickering relay F1, Fig. 6, is then energized over contact 256u1 and the supervisory lamp UL1 of the public exchange line AL1 and the line 257 (Fig. 5 and 6); the lamp extinguishes due to the high resistance of this relay. The relay chain O1-O4 is started over contact 258f1, in consequence of which the supervisory lamp again lights for a short period (the operations are not described in further detail here), and again extinguishes. A flickering of the red supervisory lamp UL1 consequently occurs, whereby the waiting condition of the public exchange line concerned is indicated. The red supervisory lamp UL2 of the second public exchange line, however, lights up permanently.

D. CONNECTING UP THE PUBLIC EXCHANGE CONVERSATION

A public exchange conversation exists between the main station and a subscriber of the public exchange on the public exchange line ALII. If an internal subscriber of the exchange is wanted by the public exchange subscriber (subscriber N3, for example), the operator presses the connecting key VT (Fig. 1) at her service station, the differential relay XB being thereby energized. (If the public exchange conversation were on the public exchange line AL1, the relay XA would be energized). Since, in the case assumed, the relay XB is energized, it causes the relay EB, Fig. 4, to energize over contact 259xb (Fig. 2). Through changing over of the contact 160eb winding I of the relay Y2, Fig. 5, energized during the public exchange conversation is without current. Relay Z2, winding II holds (through 168z2, 165eb, and 171q21) after relay Y2 opens the previous holding circuit at contact 270y2. Winding II of relay Y has not sufficient turns to maintain the relay operated, being composed of resistance wire. When relay Y2 restores, the public exchange line is broken in a backward direction through the contacts 169y2 and 170y2. The public exchange loop is simultaneously held over the contact 160q21 and contact 260y2.

When relay Y2 restores, it closes a circuit at contact 270y2 for relay An30, through contact 171q21 of the energized release relay Q21. Relay An30, at contact 272an30, places ground potential on conductors 295 of the enquiry selector RW, Fig. 6, thereby preparing the selector for operation.

When relay XB restores responsive to the release of the key VT at the main station, it permits relay EB, Fig. 4, to restore, whereupon relay Z2, Fig. 5, is restored at contact 165eb.

When the subscriber at the main station, as the

next step, dials the digit 3 to set the enquiry selector RW on the line of the desired local subscriber (substation N3), relay S2 of the trunk line ALII restores momentarily three times. Armature 152s2, Fig. 5, brings the short circuited series relay Q22 into circuit with the energized release relay Q21, whereby relay Q22 responds to the first impulse and remains operated throughout the series of impulses. At the same time, armature 281s2 is controlling the counting relays KR and LR, Fig. 6, through the shifted armature 282an30.

When series relay Q22 responds to the first impulse, it completes a circuit for relay Q30, Fig. 5, at contact 274q22, through 276an30 and 275Wi, conductor 295 being grounded as above explained. Relay Q30 closes a circuit at 260q30 for winding I of the first counting relay IR, by way of 303nr and conductor 295. Relay IR, thereupon at 286ir removes the shunt from around winding I of relay IIR, at the same time preparing a locking circuit for its own II winding.

When armature 281s2 is restored on the first impulse, winding I of the relay KR is connected up over contact 281s2, in the following circuit: earth, battery, winding I of relay KR, contacts 286ir, 283pr, 282an30, 281s2, and conductor 295 to earth. After changing over of contact 285kr and 294kr, since contact 286ir is closed (the winding II of relay IR remains connected up over this contact), the relay IIR energizes over its winding I in the following circuit: earth, battery, resistance 275Wi, resistance 287Wi, contacts 288pr, 285kr, winding I of relay IIR, contacts 290IIIr, 291Vr, 292VIIr, 293IXr, 294kr, line 295, etc., earth.

When, upon termination of the first impulse, the relay S2 again energizes, the relay LR is energized over its winding II in series with winding I of KR (contact 300kr is closed), and continues to hold over its winding I. The relay LR energizes the relay NR over its contact 302ir and this holds over its contact 303nr, so long as the selector is seized. The signalling chain of the pole changers and the ringing device is started over a contact of the relay NR (this is not described in further detail here). When, upon the second impulse, the relay S2 is again without current, the relay KR falls away, since its circuit (winding I) is interrupted. Relay LR, however, continues to hold through 284ir, 283pr, 282an30, and the restored armature 281s2. The relay IR is also without current. Further, the relay IIR is energized over its winding I over the fallen away contacts 294kr and 285kr. Upon termination of the second impulse the relay S2 again energizes relay KR, which in turn energizes relay IIR. These switching operations repeat themselves in the transmission of further impulses in such manner that the relays KR and LR are always energized after odd impulses and have fallen away after even impulses. When the impulse transmission is terminated, the relay of the relay selector which corresponds to the number of impulses (i. e., in selecting the number 3, the relay IIR) is energized for the time being. Upon the termination of impulse transmission, the relay Q22, Fig. 5, falls away with delayed action and energizes the relay PR. The slow-acting relay Q30 is also without current (the further operations as already described in connection with the house selector HW).

Testing and the first ring are limited by the time interval between the energization of relay PR and the falling away of relay Q30. If the

subscriber is free, the relay P1 (Fig. 1, bottom right) energizes over the ringing circuit. The subscriber N3 has been dialled through selection of the digit 3; there thus arises for the winding II of relay P1 (Fig. 1) the following circuit: 5 earth, battery, resistance 60Wi (Fig. 1) contacts 61c3, 62b3, 63a3, winding I of the relay X3, subscriber's station N3, choke Dr2, winding II of relay X3, contacts 64a3, 65b3, 66c3, 67wa, 68IIIr, 69IIIr3, 331q30, 332pr, winding II of 10 relay P1, earth to the source of alternating current. Through contact 333p1 a circuit is closed for the relay FRR, Fig. 6. This relay energizes and holds over its contact 334frr. The free signal is now inductively transmitted over the relay J 15 to the calling subscriber. Upon energization of relay P1, the first ring goes to the wanted subscriber, as already described. Further ringing similarly takes place in the manner already described. 20

As soon as the called subscriber removes the handset the ring-cut-off relay Ab1 energizes over its winding III, Fig. 1, as contact 331q30 has then again fallen away, and the contact 346frr has energized. Earth is connected to the line 342 23 (Fig. 4, Fig. 2) over contact 341ab1 (Fig. 4). The windings II of relays B are connected in this line. Since, in the present case, the relay An30, Fig. 5, of the public exchange junction line ALII is energized, the contact 343an30 (Fig. 2) is closed, 30 and has connected battery over the resistance 344Wi. Since in calling the subscriber N3 the relay IIIr of the enquiry selector RW is energized, the contact 344IIIr is closed, and contact 345IIIr opened. Through opening of the contact 345IIIr the short-circuit over the winding II of relay B3 is removed, so that this relay energizes. The relay A3 cannot energize over its winding II, since the contact 346an30 is opened. Through energization of relay B3 the called subscriber is 40 connected over the closed contacts 347b3 and 349b3 to the public exchange line ALIII on which the conversation lies. 45

After the main station has informed the internal subscriber that he is wanted by the public exchange, the subscriber at station N3, in order to reconnect the two separated sections of the trunk line ALII at the trunk-relay equipment of Fig. 3, presses the earthing key Te3 located at his station, whereby his relay X3 is energized. 50 The relay Eb is caused to energize over contact 350x3, while the relay B3 continues to hold. The circuit of relay B1 of the main station is broken over contact 161eb (Fig. 4), so that the main station is disconnected from the public exchange 55 line. The calling lamp in the service station extinguishes whereupon the operator hangs up the handset. The relays Y2 and Z2 reenergize over contact 160eb, so that the public exchange line is now again connected through. The subscriber's station is now connected with the public exchange subscriber. As already previously described, the public exchange line used is also here guarded against further seizure. 60

Upon the initiation of an enquiry connection, 65 therefore, (in this case it is a question of the connection of a public exchange conversation) switching means (An30, Fig. 5) become effective which bring a numerical impulse receiver (RW) over the outgoing line under the influence of the 70 speaking station holding enquiry, and prepare the coupling (over relays A or B) of the subscribers accessible over the numerical impulse receiver to the outgoing line seized by the station holding enquiry. 75

The contacts 343an30 or 346an30, Fig. 2, therefore, distinguish whether the coupling relay (A3) associated with the public exchange line ALI, or the coupling relay (B3) associated with the other public exchange line, shall become effective.

If more than two public exchange lines exist, the distinction between the coupling relays could not be effected over one relay (An30), but the coupling relays of the An-relay associated with the public exchange line concerned from time to time must be brought into effect.

The coupling relays A4, B4 and C4 are associated with the subscriber N4, not shown.

If it is found, after dialling the private branch station by the main station, that the former is engaged on an internal conversation, the main station receives in known manner the busy signal. The main station has, however, the possibility of switching itself on to the existing house conversation by pressing the key MT. This takes place as follows: through dialling the internal subscriber called in the connecting operation the pole changer PW and the relay RF, Fig. 6, were started through the relay NR. Also the short circuit for the winding I of the relay M3 and for winding II of the relay B3, Fig. 2, of the called subscribers was removed in consequence of the opening of the selector contact concerned. (The relays M2 and M4 are associated with the other subscribers). The relays M2, M3 and M4 have also a winding II. If, now, the main station momentarily presses the listening-in key MT (Fig. 4), high resistance relay Mh energizes and holds over its contact 370mh and the line 371 (Fig. 4 and Fig. 2). The sensitive relay M3 in the circuit of the relay Mh further energizes over its winding I (but not the marginal relay B3), so that the public exchange junction line is connected up over the contacts 372m3 and 373m3 to the house junction line. The connecting-up signal is inductively transmitted to the house connection over the induction winding of the relay S2.

At contacts 372m3 and 373m3, the main station is now connected to the engaged station N3. The main-station subscriber, therefore, can request the subscriber at N3 to clear out his local connection so as to receive the incoming call. As soon as the private branch station has hung up the receiver, it is automatically called, as listening-in relay Mh, Fig. 3, closes a circuit for the free relay FRR of selector RW, Fig. 6, at contact mh.

The main station is disconnected from line ALII, as before described, when the subscriber at substation N3 replies.

Listening-in relay Mh, Fig. 4, restores, along with the other relays of the main station, when the receiver is replaced.

Even in the case that the internal subscriber is occupied with a public exchange call, the main station has the possibility of entering the circuit, viz., by pressing the key MT. As already described, the relays Mh and the relay M3 energize, whereby the main station switches itself, over the contacts 372m3 and 373m3, on to the private branch station and notifies it as to the existence of the public exchange call.

For the subscriber N3 the contacts 380m2 and 381m2 correspond to the contacts 372m3 and 373m3.

E. ENQUIRY AND CHANGE-OVER

(a) Enquiry of the main station

An enquiry connection from the main station is set up in the same manner as if this station

sets up a connection, which was already described. In this connection the essential feature was laid down that, in the enquiry, switching means which connect up the enquiry selector prepare the coupling of the subscriber with whom enquiry is to be held.

Upon termination of the enquiry, the main station takes over the public exchange call by again pressing the key VT. The relay XB is then re-energized, as already described. The relay EB energizes once more and closes the circuit for the fallen-away relay Y2, Fig. 5, over the contact 165eb. When the key is again released, the relay EB falls away. The relay Z2 energizes and relays Y2 and Z2 continue to hold over the contact 270y2 (Fig. 3). By means of the relay Y2 the main station is switched back to the public exchange line. The private branch station reached in enquiry seizes the house assembly during pressure of the key of the main station, since the relay B3 has fallen away. The station called in enquiry thereupon hangs up and the main station continues the public exchange conversation.

(b) Enquiry of normal subscriber's station

If one of the internal private branch stations, N2, for example, is carrying on a public exchange conversation, for instance, on the public exchange line ALI, and if enquiry is to be held to another private branch station, the earthing key Te2, at 30 the station is to be pressed. By so doing the differential relay X2 associated with the station energizes, energizing the relay EA (Fig. 4), since its short circuit is removed through the relay GA, already energized in the existing public exchange connection, through contact 137ga. The second public exchange line cannot be influenced upon pressing the key, since the circuit for relay EB is interrupted through the energized relay T of the first public exchange line over t-contacts. 40 When the relay A2 (Fig. 2) of the subscriber N2 has energized, contact 400a2 has closed and the relay T2, winding I, has energized. The relay A3, upon energization, opens its contact 401a3 and closes its contact 402a3, whereby the relay T3, 45 winding I, energizes, while the relay A4 opens its contact 403a4, and closes its contact 404a4, and in this case causes the relay T4, winding I, to energize. (The relays T2-T4 also have each a winding II, which is connected up over contacts of the 50 relays B).

Through opening of contacts 411t2, 420t3 or 421t4, the circuit of the relay EB is broken for the time being, so that this relay cannot then energize.

As already previously described, the relay YL, Fig. 5, is without current owing to the energization of relay EA, so that the public exchange line is broken in a backward direction. The public exchange loop itself is further held. The selection of the internal subscriber now takes place in similar manner to that already described in the connection of a public exchange call through the main station. (Selection takes place over the enquiry selector RW with the assistance of relay S1). The person speaking in enquiry therefore uses, for the enquiry conversation, the public exchange junction line concerned. The operations in ringing, removing receiver and speaking are analogous to the operations already described in the setting up of a public exchange connection.

Upon conclusion of the enquiry conversation two cases may arise:

1. Ordinary enquiry, i. e., the first private

branch station again takes over the public exchange call itself.

2. Changing over, i. e., the private branch exchange called in enquiry takes over the public exchange call. In the enquiry, the first private branch station, after termination of the enquiry conversation, again presses its earthing key so that the relay EA energizes again and the relay Y1 is reenergized. After releasing the key the relay Z1 also energizes. The relay A of the second private branch station falls away through changing over of the ea-contact during key pressure of the first private branch station, so that the second private branch station is changed over to the house line. During the key pressure of the first private branch station, the second private branch station receives the busy signal in the house, since the relay R associated with the same cannot energize, due to the opened bes-contact. After receiving the busy signal the second private branch station hangs up. Through energization of relay Y1 the public exchange line is again connected through to the first private branch station, so that the first private branch station can again speak to the public exchange.

In changing-over the second private branch station takes over the public exchange conversation by key pressure. The operations are the same as those described above in the case of enquiry, with this difference, that the functions of both subscribers are interchanged, i. e., the second private branch station is connected to the public exchange over the public exchange line, while the first private branch station, upon pressure of the key of the second private branch station, receives busy signal in the house and hangs up.

If, during the public exchange conversation of a private branch station, an enquiry to the main station is necessary, the private branch station presses the earthing key and dials the main station. The signalling chain is started, and the calling lamp of the public exchange line concerned is caused to flicker dependent on the selector contact (flickering relay F1). The calling lamp lights dependent on the O1-relay of the signalling arrangement. The calling lamp flickers, therefore, dependent on the main station selected in the enquiry. Further, the public exchange alarm bell AW is caused to sound. The main station, in order to take over the enquiry conversation, presses the public exchange key of the public exchange line on which flickering is proceeding and thereby reaches, as already described previously, the public exchange line and can carry on the enquiry conversation. If the main station itself desires to take over the public exchange call upon termination of the enquiry, it presses the key VT, whereby the relay XA is energized and initiates the operation already described in preceding sections.

F. PASSING ON CALLS AND NIGHT SWITCHING

If a public exchange call arrives at the main station and if it is not answered within a certain time (about 25 seconds), the call is automatically passed on to the night station. By appropriate bridges at the distributor of the exchange it can be achieved that a call arriving on the public exchange line AL1 is automatically passed on to the first night station (subscriber N4, not shown) and the call arriving on the second public exchange line to the second night station (subscriber N5, who is similarly not shown), or that the incoming calls on both public exchange lines are

passed on only to one night station (subscriber N3).

The first class of further connection of the call will first be described. Dependent on the relays H1 and H2 of the two public exchange lines (Fig. 3) the thermo-relays Th1 and Th2 are energized. If within a time of about 25 seconds the incoming call is not answered, these relays have so far heated up that relay W11 energizes through the relay Th1 over contact 500th1, and the relay W21 energizes over the contact 501th2 of the relay Th2. The relays W11 and W21 then hold over their own contacts 226w11 and 227w12. The relay W11 energizes over its contact 502w11 and relay W12 in the following circuit: earth, battery, 1t winding of the relay W12, contact 502w11, choke Dr31, contacts 503t4, 504c4, line 23 (Figs. 2 and 4) resistance 19wi, earth.

The relay W21 connects up the relay W22 in the following circuit: earth, battery, winding of relay W22, contact 510w21, choke Dr21, contacts 511t3, closed contact 86c3, line 23 (Figs. 2 and 4), earth. The relay W12 holds over its own contact 512w12 and the relay W22 over its own contact 513w22. The ringing circuit to the night station N3 is closed over contact 67w12, while the coupling relay of the public exchange line AL1 is disconnected over contact 514w12. The night station is then called, with the assistance of the signalling device which contains the relays O1-O4. Simultaneously the white calling lamp at the main station lights up and similarly also the public exchange alarm bell AW sounds. When the night station removes the handset, the relays WA or WB previously slowly energized by alternating current energize over the continuous current now flowing in the subscriber's loop, and the WA relay holds over its contact 550wa. The relay A3 of the night station N3 energizes over contact 551wa (Fig. 2); the relay A3 then connects the night station to the public exchange junction line by means of its contacts 552a3 and 553a3, so that the public exchange conversation can proceed.

The further connection of a call from public exchange calls on the second public exchange line to the second night station takes place in the same manner with the assistance of relay WB. The relay WB holds in this case over its contact 570wb, and disconnection is effected through the contact 554wb.

The further connection of calls on both public exchange lines to the first night station (N3) is achieved by appropriate wiring at the distributor.

What is claimed is:

1. In an automatic telephone exchange, subscriber lines, trunk lines crossing each subscriber line, a connecting relay at the junction of each trunk line with a subscriber line, a dial-controlled automatic switch effective to select and operate any one of said relays, and means for associating said switch temporarily with any one of said trunk lines to enable it to be controlled thereover.

2. In an automatic telephone exchange, subscriber lines, trunk lines crossing each subscriber line, a connecting relay at the junction of each trunk line with a subscriber line, a dial-controlled automatic switch effective to select and operate any one of said relays, means for associating said switch temporarily with any one of said trunk lines to enable it to be controlled thereover, and means effective after said switch has been controlled over a trunk line to enable a selection to 75

- be made and a connection to be effected through the operation of one of said connecting relays for destroying the temporary association between the trunk line and the switch, while leaving the effected connection between the trunk line and the selected subscriber line intact. 5
3. In a branch exchange trunk-connected with a main exchange, subscriber lines, a trunk line local to the branch exchange, a group of trunk lines extending from the branch exchange to the main exchange, means responsive to the removal of the receiver on a calling branch exchange line for connecting the associated line with said local trunk line provided the local trunk line is idle, a 10 control key at the substation on the branch exchange line, and means responsive to an actuation of the said control key by the calling subscriber upon or subsequent to the removal of his receiver for transferring the connection from 15 the said local trunk line to an idle one of the said inter-exchange trunk lines. 20
4. In an automatic branch exchange trunk-connected with a main exchange, means for interconnecting a local line in the branch exchange 25 with one of the main-exchange trunk lines to permit an inter-exchange conversation, a selector common to the inter-exchange trunk lines, means controlled at will over the local line connected with an inter-exchange trunk line for bringing 30 said selector under the control of the local line by way of the connected inter-exchange trunk line, means responsive to the dialling of the number assigned to another local line from the connected local line for operating said selector to 35 bring the called local line into conversational connection with the dialling line by way of the trunk line and for signalling the subscriber on the called local line, whereby the two local subscribers may converse with each other when the 40 called subscriber removes his receiver, and means effective at the end of the ensuing conversation between the local subscribers and controllable from either local line for freeing the other local line and the said selector, leaving the unfreed 45 local line in telephonic communication with the inter-exchange trunk line. 50
5. In an automatic branch exchange trunk connected with the main exchange, means effective when an inter-exchange connection is established 55 and controllable at the will of the subscriber of the connected branch exchange line for temporarily severing the talking connection in the main-exchange line and for setting up an automatic connection between the branch-exchange end of the severed inter-exchange line and a desired other branch exchange line, and means controlled over the said other branch exchange line for re-establishing the temporarily severed main ex- 55
- change connection and for freeing the first connected branch exchange line from the connection. 6. In an automatic branch exchange trunk-connected to a main exchange, local lines in the branch exchange including normal lines and a 5 house line, inter-exchange trunks and a local trunk, push buttons at the substations on said lines, means operable dependent upon which button is pushed at the substation on the house line subsequent to the removal of the receiver for connecting the house line with the local trunk or with an idle one of the inter-exchange trunks, means responsive to the removal of the receiver at a substation on any one of the normal lines for connecting such line with the local trunk independent of push-button operation, and means responsive to the operation of the push button on the normal line accompanying the removal of the receiver for transferring the local line into connection with an idle inter-exchange trunk. 20
7. In an automatic branch exchange trunk-connected with a main exchange, local lines in the branch exchange, each of said lines having a substation thereon and a controlling push button at the substation, means normally responsive to the actuation of the push button at a substation accompanying the associated line with an idle inter-exchange trunk line pursuant to making an outgoing call to the main exchange, means controlled from an attendant's station in the branch 30 exchange for extending a connection to a desired local line pursuant to the completion of a connection incoming over a trunk line from the main exchange, and means effective under this condition responsive to the actuation of the controlling 35 push button at the called local substation subsequent to the removal of the receiver for connecting the called local line with the specific trunk line over which the call for the local line has been received. 40
8. In an automatic branch exchange trunk-connected with a main exchange, a plurality of inter-exchange trunk lines, an inquiry selector for the common use of all said trunk lines, local lines in the branch exchange, a separate group of connecting relays assigned to each of the trunk lines for interconnecting such trunk line selectively with the local line, means for taking said inquiry selector for use from any one of the inter-exchange trunk lines and for operating it to select 50 any desired one of the local lines, and means effective at the termination of the selection and dependent upon with which trunk line the inquiry selector is in association for operating the relay mechanism in the corresponding group to connect 55 the trunk line with the selected local line. 45
